UNITED STATES PATENT OFFICE.

LEO H. WISE, OF NEW YORK, N. Y., ASSIGNOR TO WISE BROTHERS, OF NEW YORK, N. Y.,
A FIRM.

OVERALLS.

No. 900,050.

Specification of Letters Patent.

Patented Sept. 29, 1908.

Application filed June 30, 1908. Serial No. 441,120.

To all whom it may concern:

Be it known that I, LEO H. WISE, a citizen of the United States, residing at New York city, in the county of New York and State of New York, have invented certain new and useful Improvements in Overalls, of which the following is a specification.

This invention relates to an improved garment for men of that kind known as overalls.

10 The ordinary overalls used by mechanics and workmen is a bifurcated garment commonly extending up to the waist, and in some cases has a breast-piece or bib which extends higher than the waist.

15 The object of the present invention is to provide for men's wear an overall garment having a breast-piece attached to the front, and a back-piece continuous with the legs and hip-portion and extending upward to 20 the shoulder, and said breast and back pieces having overlapping side-edges which are vertical under the arm-pits and are buttoned together and entirely envelop the body of the wearer, the garment comprising 25 what may be termed a coverall.

Referring to the accompanying drawing, Figure 1 is a front view of the garment. Fig. 2 is a side view of the garment. Fig. 3 is a cross section at the breast on line 3—3.

30 The legs, 1, and front pockets, 2, are of the usual construction; at the front is a waist-band, 3, which extends only across the front and whose ends terminate at the vertical side-edges, 15. There is no waist-band at 35 the back. The fly opening, 5, at the front extends vertically from the crotch, 6, to the said waist-band, 3; in this garment the "fly" is a mere vertical slit or opening with lapped edges which are fastened by buttons. Both 40 ends of the fly-slit are closed,—the top-end being closed at the waist-band as the lower end is at the crotch.

Above the waist-band at the front is a breast-piece, 7, made of two side-parts, 8, 8, 45 which are united together at the center by a vertical seam, 9, and said breast piece at its lower edge is attached to the waist-band, 3, and extends upward to the point, 10, where the neck of the wearer would come. The 50 breast-piece has vertical side-edges, 15.

By making the front breast-piece of two equal parts, 8, and uniting them with a vertical seam, 9, and attaching the same to the waist-band, 3, at the front, the desired con- 55 vex conformation is obtained.

The back is made of two pieces united at the center by a vertical seam, 14; each back piece comprises the back of one leg, 1, the hip, 11, and one half of the back of the body, 12, to the shoulder, 13; these parts being one 60 continuous piece.

The leg-fronts and backs at the outside seams, 16, are permanently united from the lower ends of the legs up to the front pockets at the point, 17. From said points, 17, adjacent the front pockets, upward, the vertical side-edges, 15, of the body-front overlap the side edges of the body-back and these side-edges, 15, which have vertical 70 position under the arms, are secured together by buttons, 18; both the front and the back have inclined corner edges, 19, which extend from the highest or neck-edges, 10, 20, down to the side-edges, 15. These inclined corner edges form the curves that take under the arms of 75 the person. Shoulder straps, 21, extend from the top back-edge, 20, to the top front edge, 10.

It will be seen this overall garment has a construction that provides for enveloping 80 the legs and body, and covers the front and back to the neck. Its construction also is such as to make it convenient to put on and take off.

Having thus described my invention what 85 I claim and desire to secure by Letters Patent is,—

1. An overall garment for men comprising the leg-fronts; the breast-piece made of two parts, 8, united by a central vertical seam 90 and having vertical side edges, 15, that take vertical position under the arm-pit of the wearer and a waist-band at the front only connecting said leg-fronts and breast-piece and the ends of the said front waist-band 95 terminating at the aforesaid side edges; and the leg-backs, hip-parts and body-backs consisting of two pieces each continuous from the lower ends of the legs to the shoulder and united together at the body-back by a center 100 vertical seam, 14, and having vertical side edges which overlap the side-edges of the said breast-piece under the arm and button thereto.

2. Overalls for men comprising the leg- 105 fronts having front pockets and provided with a fly-opening; a breast-piece made of two parts, 8, united by a central vertical seam and having side edges, 15, that take vertical position under the arm-pit of the 110

wearer; a waist-band at the front only connecting said leg-fronts and breast-piece and extending across the top of the fly-opening and the ends of the said waist-band terminating at the aforesaid side edges; and two back pieces each continuing from the lower end of the legs upward to the shoulder and neck and united to the leg-fronts by an outside seam, 16, extending from the lower edge to the upper part of the front pockets, and therefrom having upward-extending free vertical side-

edges which underlap the vertical side edges of the said breast-piece, and the uppermost part provided with inclined edges, 19, extending to the arm-pit.

15

In testimony whereof I affix my signature in presence of two witnesses.

LEO H. WISE.
